LAST LATHE

Filed May 7, 1923

Inventor:

Charles P. Morton

By Walter D. Murray
Attorne

UNITED STATES PATENT OFFICE.

CHARLES P. MORTON, OF CINCINNATI, OHIO.

LAST LATHE.

Application filed May 7, 1923. Serial No. 637,142.

An object of my invention is to provide a simple and efficient last lathe structure.

Another object of my invention is to provide a direct drive of the cutter head.

Another object of my invention is to provide a device wherein the disadvantages incident to the disposition of the axis of the cutter head in a horizontal plane will be obviated by providing means for mounting the cutter head with its axis in a vertical plane.

These and other objects are attained by the means described herein and disclosed in the accompanying drawings, in which:

Fig. 1 is a perspective view of a cutter head and driving mechanism therefor embodying my invention, together with a fragment of the ways of a lathe bed upon which same are mounted.

Fig. 2 is an enlarged perspective view of a cutter head frame, parts being broken away, and embodying my invention.

Fig. 3 is a perspective view of a cutter head plate forming a detail of my invention.

In the usual last lathe construction a carriage 4 is provided for carrying the cutter head 5 in a suitable manner and in a position to engage a block from which the last 6 is being turned. This carriage is reciprocally mounted on ways 7 and 8 formed on supporting frame members 9 and 10 of the lathe bed. My invention deals with the mounting of the cutter head 5 and the means for rotatably actuating same. The carriage 4 carries a depending bracket 11 upon the lower end of which a motor 12 is mounted for vertical adjustment. The motor shaft 13 is disposed in a vertical plane and preferably is elongated to such extent that it will project through an aperture 14 formed in the carriage 4. The bracket 15 is mounted in a way 16 formed in the upper face of the carriage 4 for adjustment transversely of the carriage, and carries a journal bearing 160 supporting a suitable bearing block 17 for the upper end

of the motor shaft 13. The upper end of the motor shaft has mounted upon it the cutter head frame 18. Any suitable mounting means may be provided for example by providing a shank 19 upon the cutter head frame, the shank having a threaded bore 20 for the reception of the complementary threaded upper end of the motor shaft 13. The cutter head frame comprises a plurality of radially extending wings 21 upon each of which may be mounted semi-circular discs 22 having formed at their peripheries arcuate cutting edges 23. Any suitable means may be used for mounting the cutters upon the frame, for example bolts may be passed through the apertures 24 provided in discs 22 and lodging in suitable bores 25 in the cutter head frame.

The operation of the device is obvious. Any suitable means for effecting high speed of the motor may be employed.

Although I have shown the cutter head as mounted directly upon the upper end of the motor shaft, my invention is not restricted to this direct mounting although it is preferable to have a direct drive.

What I claim is:

In a last lathe the combination with a lathe bed, of a carriage reciprocally mounted on the lathe bed and having a bore therethrough, a depending bracket mounted on the bottom of the carriage, a vertical motor carried by the depending bracket and having an elongated vertical armature shaft extending upwardly through the bore in the carriage, a bearing bracket adjustably mounted upon the upper side of the carriage for receiving the projecting end of the armature shaft, and a rotary cutter mounted on the free end of the armature shaft adapted to engage the side of the horizontally arranged work.

In testimony whereof, I have hereunto subscribed my name this 3rd day of May, 1923.

CHARLES P. MORTON.
